UNITED STATES PATENT OFFICE.

JOHN E. O'BRIEN AND CHARLES HARTER, OF ST. LOUIS, MISSOURI.

CAR-ROOF.

1,154,425.

Specification of Letters Patent. Patented Sept. 21, 1915.

Application filed September 19, 1914. Serial No. 862,506.

To all whom it may concern:

Be it known that we, JOHN E. O'BRIEN and CHARLES HARTER, citizens of the United States, residing at the city of St. Louis, State of Missouri, have invented a certain new and useful Improvement in Car-Roofs, of which the following is a full, clear, and exact description, such as will enable others skilled in the art to which it appertains to make and use the same, reference being had to the accompanying drawings, forming part of this specification, in which—

Figure 1 is a transverse section taken through the upper portion of a freight car, the same being provided with a roof of our improved construction. Fig. 2 is an enlarged detail section taken on line 2—2 of Fig. 1. Fig. 3 is a detail plan view of a portion of the fabric forming a part of our improved roof and showing the opening formed therein for one of the running board saddles. Fig. 4 is an enlarged transverse section taken through the central portion of the roof and one of the running board saddles thereon. Fig. 5 is an enlarged cross section taken approximately on the line 5—5 of Fig. 4. Fig. 6 is an enlarged detail section of a portion of the roof. Fig. 7 is a detail sectional view of an inside roof constructed in accordance with our invention.

Our invention relates to car roofs and more particularly to the outer surface or roof covering, the principal object of our invention being to provide a comparatively simple and inexpensive car roof having an outer covering member which is formed in one piece, thus eliminating the necessity of forming joints which, as is well known, tend to open under the strains and vibrations to which car roofs are ordinarily subjected and as a result, the roofs become leaky and necessitate frequent repairs.

Further objects of our invention are to form a car roof in one piece and of flexible material so that it will readily give or yield to the twisting and uneven movement of the roof boards which movement is caused by the strains and vibration imparted to the superstructure of the car during transit, and further to provide a roof which can be easily and cheaply applied and can be repaired without requiring special tools and the services of skilled workmen.

With the foregoing and other objects in view, our invention consists in certain novel

features of construction and arrangement of parts hereinafter more fully pointed out.

Referring by numerals to the accompanying drawings, 10 designates the side walls of an ordinary freight car; 11, the top side plates thereof; 12, the facia plates; 13, the end plate, and 14 the roof boards, all of which parts are of ordinary construction. Applied to the upper portion of the facia plates at the sides and ends of the car is an ordinary, half-round molding strip 15. The roof covering as contemplated by our invention comprises a comparatively thin body 16 of self-hardening plastic material in which is embedded a reinforcing element 17, preferably in the form of wire fabric or textile, such as burlap or canvas. This section of wire fabric or textile is of sufficient size to cover the entire roof of the car and the edges of said section are extended downward over the molding strip 15, said edges being attached to the facia plates in any suitable manner.

To accommodate the transverse blocks 18, which serve as running board saddles, rectangular openings 19 are formed in the section of fabric or textile and in order to close these openings, caps 20 of self-hardening plastic material, having embedded therein a section of wire fabric or textile, are formed, said caps being of sufficient size to receive the saddles 18. There is slight clearance between the sides and ends of the saddle and the corresponding walls of the cap in order to permit relative movement of the parts. The lower edges of these caps are extended outwardly as designated by 21, and said edges are attached to the body of the roof covering in any suitable manner, preferably by means of rivets. After these caps have been properly applied to the main body of the covering, the edges 21 are preferably coated with self-hardening plastic material in order to form an air and dust tight joint between the edges of the cap and the body of the roof covering.

In the manufacture of our improved car roof it may be found advantageous to form the roof covering separately from the car and to apply said covering after the roof boards have been placed in position, in which instance, it will be necessary, of course, to permit the plastic material to become set and hardened before said roof covering is applied. However, it may be desirable to

2

form the roof covering directly on the roof boards and where such procedure is carried out, a layer of comparatively thin paper 22 is laid directly on the roof boards, after which a thin coating of self-hardening plastic material is laid directly on said paper. The single section of wire fabric or textile is now placed on the coating of plastic material and a second coating of said plastic material is applied to the fabric or textile. The edges of the covering are brought down and attached to the facia plates, said edges being finished with a coating of self-hardening plastic material and the running board saddles are covered with the caps, as hereinbefore described. Thus the roof covering is applied directly to the roof boards and after said covering has become set and hardened a very strong and durable roof is provided. The layer of paper 22 prevents the first layer of plastic material from adhering to the roof boards and consequently when the car is in service and subjected to strains and vibrations, the roof covering is capable of movement independently of the roof boards.

Our improved construction entirely eliminates the formation of soldered or nailed joints, such as are necessary in the formation 30 of sheet metal car roofs, and by forming a one-piece roof, leakage resulting from loose or ruptured joints is done away with.

It will be understood that the roof portion of a car is subjected, not only to horizontal 35 movement independently of the superstructure, but to twisting and torsional movement resulting from the service strains and vibrations imparted to the car body and such movement naturally affects the roof covering. Where such a covering is made in sections, the joints between the same readily open under the uneven movement imparted to said covering, but by our improved construction, the entire roof covering, being 40 flexible to a certain degree, can readily yield and give in any direction and as a result the life or term of service of a roof of this construction is much greater than a sectional or jointed roof.

50 In the foregoing description, we have described what is known as an "outside" roof, and while this construction is generally desirable, it will be understood that our invention can be utilized in the construction 55 of an inside roof, *i. e.*, the body of self-hardening plastic material with the embedded fabric applied to the inside of the roof boards, as shown in Fig. 7, and if found necessary, the inside covering can be supported by carlines or the like.

60 The self hardening plastic material utilized in the formation of our improved roof may be composed of various combinations of ingredients, it only being necessary that 65 said material be practically water and

weather proof and flexible to a certain degree when dry, and in experiments and practice we have obtained satisfactory results in the use of a compound ordinarily known as roofer's cement, the same being a mixture 70 of powdered or pulverized asphalt, powdered or pulverized asbestos, crude oil, and a suitable drier such as japan. In some instances it may be found desirable to include with the above mentioned mixture, a certain per cent. 75 of ordinary Portland cement.

A roof of our improved construction is comparatively simple, can be cheaply manufactured, and can be readily repaired.

It will be readily understood that minor 80 changes in the size, form and construction of the various parts of our improved roof can be made and substituted for those herein shown and described, without departing from the spirit of our invention, the scope 85 of which is set forth in the appended claims.

We claim:

1. As a new article of manufacture, a car roof covering comprising a body of self-hardening plastic material in which is embedded a reinforcing fabric, which body of plastic material with the embedded fabric is of sufficient size to cover the entire roof and caps formed of self-hardening plastic material having reinforcing fabric embedded 95 therein, which caps are located in the center of said roof and are adapted to receive the car roof running board saddles.

2. As a new article of manufacture, a car roof covering comprising a single section of 100 fabric of sufficient size to cover the entire roof, a body of self-hardening plastic material in which said fabric is embedded, the edges of said roof covering being extended downward so as to over-lie the upper portions 105 of the car body superstructure, and the central portion of said roof being provided with caps adapted to receive the car roof running board saddles.

3. A car roof covering comprising a single 110 section of fabric of sufficient size to cover the entire roof, a body of self-hardening plastic material in which said fabric is embedded, there being a series of openings formed in the central portion of said covering to accommodate the running board saddles, and upwardly projecting caps rigidly fixed to the roof covering around said openings, said caps being formed of sections of fabric embedded in self-hardening plastic material. 115

4. A car roof covering comprising a single 120 section of fabric of sufficient size to cover the entire roof, a body of self-hardening plastic material in which said fabric is embedded, there being a series of openings formed in the central portion of said covering to accommodate the running board saddles, upwardly projecting caps rigidly fixed to the roof covering around said openings, said caps being formed of sections of 125 fabric embedded in self-hardening plastic material.

5 fabric embedded in self-hardening plastic material, and said roof covering being provided with depending edges which overlie the ends of the roof boards and a portion of the car body superstructure to which the roof covering is applied.

5. The combination with a car roof covering comprising a single section of fabric of sufficient size to cover the entire roof, and
10 a body of self hardening plastic material, in which said fabric is embedded of a series of running board saddle caps projecting upwardly from said roof covering, the edges of which caps are bonded to said covering.
15 6. As a new article of manufacture, a car

roof covering comprising a body of self hardening plastic material in which is embedded a reinforcing fabric, and a series of running board saddle caps forming a part of said car roof, the edges of which caps are 20 bonded to the body of the roof covering.

In testimony whereof we hereunto affix our signatures in the presence of two witnesses, this 15th day of September, 1914.

JOHN E. O'BRIEN.
CHARLES HARTER.
